CIRCUIT-CLOSING MECHANISM.

No. 839,216.

Specification of Letters Patent.

Patented Dec. 25, 1906.

Application filed May 17, 1905. Serial No. 260,773.

To all whom it may concern:

Be it known that I, THOMAS W. SMALL, a citizen of the United States, residing at Cleveland, in the county of Cuyahoga and State of Ohio, have invented a certain new and useful Improvement in Circuit-Closing Mechanism, of which the following is a full, clear, and exact description, reference being had to the accompanying drawings.

The object of the invention which forms the subject of this application is to provide means for closing a local circuit automatically.

The mechanism shown is particularly applicable for closing local circuits on electric cars in which the closing is effected by means of attachments in the path of the trolley. A practical application of my device is that of closing local circuits in street-cars for the purpose of actuating street-indicating or sign mechanism, carried by the car.

Referring to the accompanying drawings, Figure 1 represents in perspective a form of my device attached to the supporting cross-wire in an overhead-trolley system, showing the position of the parts immediately after the trolley-wheel has passed the circuit-closer. Fig. 2 is a front elevation of the same. Fig. 3 is a top plan view.

In the various figures, A represents the current-wire supported by the transverse cross-wire B and connected therewith by the usual insulating-spool C and hanger C². Embracing the neck of the spool C and beneath the transverse wire B is a yoke-shaped plate D. Above the plate D and the wire B and likewise engaging the neck of the spool C is a second yoke-shaped plate E, secured by suitable means, such as bolts F, to the plate D. The legs of these two plates D and E are projected in opposite directions, and this arrangement produces a very firm and rigid attachment.

The plate E is made of some suitable conducting material and has pivotally secured to its legs E' E' conducting contact-shoes E² E². These contact-shoes are preferably provided near their free ends with guides E³ E³, which play in suitable openings in the plates D and E and are provided at their upper ends with stops E⁵, limiting their downward movement. About the guides E³ and between the shoes E² and the plate D are

compression-springs E⁴ E⁴ for the purpose of pressing the shoes downward, so as to effect a firm contact with the terminal pieces of the local circuit, which are in the instance shown supported by the trolley-harp, as will be hereinafter described.

Referring to Figs. 1 and 2, H represents the ordinary trolley-pole, surmounted by the trolley-harp H² H², carrying the usual trolley-wheel H³. At the tips of the harp-prongs and insulated therefrom by suitable insulation H⁴ are the terminal pieces H⁵ H⁶ of the wires J' and J², respectively, which lead to a local source within the car. These wires J' and J² are suitably insulated and may be led down the interior of the trolley-pole or suitably secured about the same in any convenient manner.

From the description above the operation of the device will be obvious. Whenever the car passes under the circuit-closing device the terminals H⁵ H⁶ will pass under the shoes E² E² and elevate them somewhat. During this period the shoes are kept in firm contact with the terminals by the pressure of the springs E⁴. While this contact is maintained the circuit from the source of the wires J' J² will be closed through the terminals H⁵ H⁶, the shoes E² E², and the conducting-yoke E' E E'.

By the foregoing means it will be seen that I have provided a simple and practical device whereby mechanism, such as street-indicating devices, carried within the car may be actuated automatically from the exterior. For this and many similar signaling purposes my structure is well adapted, as will be apparent on inspection.

It will be understood that many modifications of design and substitution of mechanical equivalents may be made according to the particular necessities of the situation without departing from the spirit of my invention or altering the character thereof.

Having described my invention, I claim—

1. In mechanism for establishing a local circuit through a moving vehicle, a circuit-closing device, attached near but insulated from the main-current wire, said device including a metallic frame and a pair of contact members in electrical contact therewith, and a trolley-pole carrying insulated terminals of the local circuit in such manner as

to make contact with the circuit-closing device.

2. In mechanism for establishing a local circuit through a moving vehicle, a conducting-plate adapted to straddle the neck of an ordinary supporting-spool, a second plate adapted to likewise straddle said spool, and securing means adapted to hold these plates together when placed astride said spool in opposite directions.

3. In mechanism for establishing a local circuit through a moving vehicle, a circuit-closing plate provided with a yielding contact prong and a supporting-plate so constructed that the parts may be securely attached to the insulating-spool supporting a main-current wire.

4. In mechanism for establishing a local circuit through a moving vehicle, a circuit-closing strip attached to a suitable support

in the path of a trolley-pole and carrying contacts placed in the path of the trolley-harp, terminal pieces on the trolley-harp adapted to brush against the contacts and wires attached to the terminals on the trolley- 25 harp.

5. In a mechanism for establishing a local circuit through a moving vehicle, the combination of a U-shaped plate, a pair of curved contact-bars pivoted to the plate at its projecting ends, bolts loosely holding the bars near their free ends to said plate, and springs under compression surrounding said bolts. 3c

In testimony whereof I hereunto affix my signature in the presence of two witnesses. 35
